UNITED STATES PATENT OFFICE.

DAVID VICTOR, OF ST. LOUIS, MISSOURI.

BOX AND CRATE OPENER.

1,209,520.

Specification of Letters Patent. Patented Dec. 19, 1916.

Application filed June 1, 1916. Serial No. 101,148.

To all whom it may concern:

Be it known that I, DAVID VICTOR, a citizen of the United States, residing at St. Louis, State of Missouri, have invented 5 certain new and useful Improvements in Box and Crate Openers; and I do declare the following to be a full, clear, and exact description of the invention, such as will enable others skilled in the art to which it 10 appertains to make and use the same.

This invention relates to improvements in tools used for opening boxes, crates and the like, and has for its principal object to provide a simply constructed article which, 15 while it can be very inexpensively manufactured will be very efficient in operation.

An additional object is to provide a tool of this character provided with an improved nail pulling means.

With these and other objects in view the invention resides in the novel features of construction which will be hereinafter more particularly described and claimed as shown in the drawing wherein:

Figure 1 represents a plan view of a tool constructed in accordance with my invention; Fig. 2 is an edge view thereof; Fig. 3 is a transverse section on the line 3—3 of Fig. 1; and Fig. 4 is a detail longitudinal section on the line 4—4 of Fig. 1.

In the preferred embodiment my invention comprises a one-piece tool having a handle 1 upon one end of which is formed a head 2 of any ordinary or preferred construction. In the present instance I have shown a handle provided with a combination hatchet and hammer head, the cutting blade being designated by the numeral 3. As shown in the several figures of the drawing, one side of the handle 1, which for the sake of convenience I will designate as the bottom, is flat. Also one side of the head 2 is flat and formed flush with the flat bottom side of the handle 1 so that when the 45 tool is placed on a plane surface the parts thereof will contact therewith. The hammer portion of the head 2 is enlarged as shown at 4 so as to facilitate the use of the tool in driving nails or the like. The opposite end of the handle is tapered at its free end as shown at 5 so as to form a thin edge for insertion beneath the tops of boxes and the like in order to lift the same. This end is also provided with a V-shaped notch 6 for pulling nails and the like. Furthermore, this end of the handle on each side of

the notch may be conveniently used as a screw driver.

Openings 7 are formed in the handle 1 at points spaced from the ends thereof, said openings being substantially rectangular in plan view and extended longitudinally of the handle. These openings extend entirely through the handle as shown at 8 and contain the nail pulling means, the means in each being substantially alike.

From each outer end wall of the openings 7 extends a relatively thin tongue 8', said tongues extending inwardly into the openings and having their bottoms in the plane of the bottom of said handle. These tongues have their inner end formed substantially V-shaped with the apices thereof extending inwardly, the lengths of said tongues being slightly less than one-half the length of the opening.

On the side walls of each opening are formed the wings 9, the latter extending from points adjacent the sides of the V-shaped tongues to points substantially in the middle of the openings. As shown in Fig. 1 the inner edges of the wings are arcuate in shape and disposed rather close to the edges of the V-shaped portions of the tongues, thus providing diverging notches 10 in which the nails to be pulled are adapted to be gripped. From Fig. 4 it will be noted that the bottoms of these wings 9 are also in the plane of the bottoms of the handle 1 of the tool, and that both the edges of these wings and the edges of the V-shaped portions of the tongues are inclined or beveled downwardly so as to readily slide beneath the head of the nail to be pulled. By providing the wings 9 as shown and forming the notches 10 very narrow at their ends, the nails will be readily guided into one of these notches and effectively gripped beneath the head so that the latter is relieved of a portion of the strain caused by pulling. This will prevent the head of the nail from being broken off.

The openings 7 in which the nail pulling means are disposed are placed such a distance away from the ends of the handle that the nails will be pulled almost straight up. This allows them to be removed with greater ease and also permits them to be used over again as they are not bent. Two nail pulling means are formed in the handle in order to facilitate the removal of the nails as in this way the nail may be pulled re-

gardless of which end of the tool is held in the hand.

From the foregoing description it is obvious that I have invented an extremely simple, yet very efficient box opener which can be very inexpensively manufactured and marketed.

I claim:

10 A tool of the class described having a handle flat on its opposite sides and provided with a longitudinally extending rectangular opening therein, a relatively thin tongue extending into said opening from one end wall thereof, the bottom of said tongue being in the plane of the bottom of the handle, the inner edge of the tongue being V-shaped with the apex therein extending inwardly, said tongue being less

than one-half the length of said opening, and wings of a thickness equal to that of the 20 tongue formed on the side walls of said opening adjacent each side of said tongue, the inner edges of said wings being arcuate, thereby forming diverging notches between the edges of said tongue and said wings, 25 said wings being substantially equal in length to one-half the length of said opening, the edges of said wings and the tongue being inclined downwardly.

In testimony whereof I have hereunto set 30 my hand in the presence of two subscribing witnesses.

DAVID VICTOR.
